RHEOSTAT OR POTENTIOMETER

Jesse Marsten, Philadelphia, Pa., assignor to International Resistance Company, Philadelphia, Pa., a corporation of Delaware

Application January 12, 1934, Serial No. 706,343

27 Claims. (Cl. 201—55)

The invention relates to rheostats, and/or potentiometers, and, with respect to its more specific features, to rheostats and/or potentiometers for use in connection with audio and radio frequency apparatus to control the intensity of the sound waves.

One object of the invention is to provide, in a variable resistance device, a contact which will short-circuit a minimum portion of the resistance element or in which the sum of resistance on both sides of the variable contact shall be, as nearly as possible, equal to the total resistance of the resistance element.

Another object of the invention is to provide a variable resistance device giving a smooth uniform change of resistance as the movable contact is moved. Another object of the invention is to provide a variable resistance device which will give a minimum amount of noise in an audio circuit. Another object of the invention is to provide a type of contact area which consistently makes contact at the same point or points of the area and maintains absolute uniformity of change of resistance in accordance with the resistivity at each part of the resistance device.

Another object of the invention is to provide a device of the character indicated, of extremely simple and durable construction. Another object of the invention is to provide a device of this class subject to a minimum amount of wear of the resistance element in use in order that the device shall have a long "life". Another object of the invention is to provide a construction for a rheostat and/or potentiometer and switch readily susceptible to variation in embodiment so far as the resistance curves are concerned to accommodate the varying needs of purchasers thereof. Another object of the invention is to provide an effective and reliable manner of making the electrical connection between fixed terminals and the resistance element. Another object of the invention is to provide a means for introducing a tap at any point along the resistance element between the end terminals without interfering with the smooth movement of the movable contact element or in any manner destroying the symmetry of surface of the resistance element. Another object of the invention is to provide a resistance element and a contact adapted to form a good path for the current at the contact point subject to a minimum of wear while in use and a minimum of change due to passage of time or conditions of the atmosphere. Another object of the invention is to provide a rheostat and/or potentiometer and switch readily adaptable for instal-

lation in commercial radio sets and which may be easily connected in circuit therein as desired. Other objects will be in part obvious or in part pointed out hereinafter.

The invention accordingly consists in the features of construction, combinations of elements and arrangement of parts and in the several steps and relation and order of each of said steps to one or more of the others thereof, all as will be illustratively described herein, and the scope of the application of which will be indicated in the following claims.

In the accompanying drawings, in which is shown one of various possible embodiments of the mechanical features of this invention,

Figure 1 is a rear elevation of the rheostat;

Figure 2 is a cross-sectional view taken on the line 2—2 of Figure 1;

Figure 3 is a plan view of the resistance element;

Figure 4 is a developed view of the periphery of the insulating disc and resistance element with connections;

Figure 5 is a perspective view of a contact brush;

Figure 6 is a front elevation of the insulating base;

Figure 7 is a rear elevation of the insulating base;

Figure 8 is an elevation of the commutator disc and contact fingers;

Figure 9 is a side elevation of the commutator and contact fingers and operating shaft;

Figure 10 is a sectional view through a radio panel showing the rheostat mounted in elevation;

Figure 11 is a sectional view through the metal casing showing a snap switch device in elevation;

Figure 12 is a sectional view on the line 12—12 of Figure 11 (with the parts in a different position) showing the switch actuator in elevation;

Figure 13 is a diagrammatic view illustrating the construction of the resistance element and its relation to the various contacts;

Figure 14 is a view similar to Figure 13, being however a cross-sectional view taken on the line 14—14 of Figure 13;

Figure 15 is a plan view of a terminal;

Figure 16 is a diagrammatic view of the resistance element and certain contact making devices, viewed as from the front of a radio set in which the apparatus is installed.

Similar reference characters refer to similar parts throughout the several views of the drawings.

Referring first to Figure 2, I provide an in-

lating support or plate 10 for mounting the electrical and mechanical elements of the rheostat. This support or plate 10 may be made of any suitable insulating substance; however I prefer to make it of moldable material in order that the several parts thereof, hereinafter pointed out, may be made in a single piece reducing cost and eliminating the possibility of mechanical vibration. Among substances suitable for this purpose are molded hard rubber and artificial resins; because of its excellent insulating properties and the ease with which it may be formed I prefer one of the phenolic condensation products, such products being hereinafter generally designated by the name "phenol".

The support 10 is, in the illustrative embodiment of the invention herein disclosed, substantially a disc having a hole 11 therethrough at the center. As shown by a comparison of Figures 2, 6, and 7, the hole 11, which is round, merges at the rear of the support 10 with a hexagonal recess 12 the bottom of which forms a shoulder 13. I provide a brass bushing 14 which fits in the hole 11 and which has a hexagonal head 15 fitting in the recess 12. The bushing 14 has a cylindrical portion 16 of substantially the same length as the hole 11, this cylindrical portion 16 being bounded by a shoulder 17. I secure the plate 10 and bushing 14 together by inserting the bushing in the plate, as shown in Figure 2, and forcing the metal of the shoulder 17 outwardly with a suitable tool; thus the bushing and the plate are permanently locked together.

The bushing 14 constitutes a journal for a shaft 18 as shown in Figure 2. Angular movement of this shaft 18 causes the resistance in circuit to be varied as will hereinafter appear; it is the control shaft for controlling the intensity or volume of sound of the radio or other audio frequency apparatus, and in this particular embodiment of the invention it also controls the main switch of the apparatus. Still referring to Figure 2, one end of the shaft 18 has a portion 19 of reduced diameter leaving a shoulder 20. An insulating disc 21, preferably of canvas phenol or other strong insulating substance, is attached to the end of the shaft 18, resting against the shoulder 20 and securely fastened in place by heading over the portion 19, so that the disc 21 rotates with the shaft 18.

Referring now particularly to Figure 8, I provide a commutator and movable contact member 22 made out of a single piece of metal having contact arms 23, 23, 23 as an integral part thereof. The member 22 is of metal so that it shall be conductive, and of sheet metal in order that it may be readily and cheaply manufactured and in order that the contact arms 23 may incorporate means for securing spring pressure against the resistance without the introduction of further separate members involving a movable contact. It will be readily appreciated that it is desirable to keep the number of separate electrical elements as low as possible consistent with other features in order that the device shall not be microphonic in an audio circuit. Furthermore, the member 22 is preferably made of a non-oxidizable metal and for reasons which will hereinafter appear, a metal which shall not release an oxidizable deposit. It is also to be noted that the conductivity of the member 22 should be good, and that expensive metals are desirably not employed. I prefer to use Monel metal for

the member 22, being an alloy of copper and nickel, and possessing all the above desired characteristics, which has, furthermore, proved satisfactory in use. I have found that nickel is also satisfactory.

Referring again to Figure 8, the member 22 is roughly a disc having an outward projection 24 from which the three contact arms 23 extend in a substantially circumferential direction. Comparing Figure 8 with Figure 9 it will be noted that the arms 23 are inclined with respect to the plane of the member 22.

The member 22 is securely fastened to the insulating disc 21 by means of a plurality of hollow rivets 25, located in holes 26 (see Figure 8). The member 22 is insulated from the shaft 18 by reason of the fact that the head of the portion 19 of reduced diameter is spaced from the member 22 which has a central hole 27 therein. Comparing Figures 8 and 2, there is a projection 28 at right angles to the plane of the member 22 which is formed by pressing out the metal of the member 22 from a rectangular part 29 thereof which merges with the hole 27. This projection 28 constitutes a stop to limit the movement of the shaft 18 and all parts carried thereby in either direction, contacting with a stationary stop which will be presently described. As best shown in Figure 2 one of the rivets 25 constitutes the end of a short rod 30 which projects at right angles to the surface of the member 22 on the side opposite that from which projects the projection or stop 28 and the arms 23, and this rod is the actuator for a switch as will be presently described.

Considering now Figures 1, 2, and 3, I provide a resistance device in the form of a flat broken annulus or horseshoe 31. This flat broken annulus, having somewhat the shape shown in Figure 3, constitutes a track for the movement of the arms 23 thereon and in electrical contact therewith. The nature of the surface and resistance material of this resistance strip will be more fully pointed out hereinafter, but at the present time I point out that it preferably consists of a strip of impervious insulating substance unaffected by moisture, and I have found phenol to be very satisfactory. The surface of this insulating substance is covered with a conductive resistance material preferably of a carbonaceous nature.

For the attachment of the resistance 31 and the electrical connection of its two ends in circuit I provide combined mounting members and terminals consisting of rivets 32 having a broad under surface engaging the top of the resistance 31, and extending through the insulating support or plate 10 and also holding in position bendable sheet metal projecting terminals 33 for the connection in circuit of the device. These terminals 33 are best shown in Figure 16 and comprise an enlarged portion 34 having a hole therein and a long shank 35 having a hole at the end thereof. Referring now to Figure 6 the enlarged portions 34 of the terminals 33 fit in recesses 36 in the insulating substance with their shanks 35 extending through grooves 37 that merge with the recesses and thus they are held from angular motion.

A third terminal 38 like the terminals 33 is located between them and positioned in a recess 39 like the recess 36 which has merging with it a groove 40 like the grooves 37 and this terminal is held in position by a rivet 41 like the rivets 32; as shown in Figure 1 the broad head of the rivet 41 secures in place a Y-shaped brush 42, pref-

erably made of phosphor bronze, which is shown in perspective in Figure 5 and has contact surfaces 43 contacting the under portion of the commutator and movable contact member 22 to connect it and its arms 23 in circuit. The phosphor bronze Y-shaped brush 42 is not only a good conductor and makes an excellent non-microphonic contact with the movable commutator member 22, but it also is resilient and constitutes a spring to keep the contact surfaces 43 pressed against the bottom of the member 22.

In many apparatus it is desirable to use a single variable resistor in two circuits, or to use portions of the variable resistor element in different circuits, and therefore to establish an electrical connection with the resistance element of the rheostat somewhere between its end terminals. To that end I provide means to tap into the resistance element 31 at any desired point, comprising a terminal 46 (Figure 15) having projections, ridges, upset portions or the like, which is held in place by a rivet 47 like the rivets 32, only shorter, and which, as shown in Figure 2, establishes contact with a piece of sheet metal 48 which 25 in turn makes contact with the resistance 31 in a manner which will be more fully pointed out hereinafter. The ridges in the terminal 46 cause it to grip the insulating base 10 so that it is as firmly held in place as the other terminals, but 30 it can be located anywhere.

From the foregoing description it will be seen that rotation of the shaft 18 causes the contact arms 23 to travel over the surface of the resistance 31. The contact arms 23 can be connected 35 to receive current, positive, negative or alternating, by means of the terminal 38 and connections described including the Y-shaped brush 42 and commutator and movable contact member 22. One or the other or both ends of the resistance 31 40 can be connected in circuit, as desired, through the terminals 38 and rivets 32, and current can also be taken off the resistance element 31 at any desired place by means of the terminal 46 and piece of sheet metal 48.

45 Referring to Figure 7, on the back of the insulating support or plate 10 I provide a trapezoidal projection 50 molded integral with the plate 10, and this is contacted by the projection 28 to form a mechanical stop limiting movement of the 50 parts in each angular direction.

Referring now to Figures 10 and 11, I preferably provide a sheet metal casing 51 covering the operating parts of the rheostat and also serving to support a switch which will be presently described. The sheet metal casing 51 is in the form 55 of a cylindrical cup as shown by Figures 10 and 11, and, referring to Figure 10 in connection with Figure 6, is provided with three integral bendable metal tabs 52 received in three corresponding recesses 53 on the front of the plate 10, the tabs 60 being bent over in position in the recesses to secure the parts together, and the lip of the cup 51 being received against an annular shoulder 54 in the plate 10 which is best shown in Figure 2.

65 The entire device is adapted for attachment to a radio panel with the rheostat and casing 51 on the inside of the radio receiving apparatus and the shaft 18 projecting outside thereof. These panels of radio apparatus, represented by 70 the numeral 55 in Figure 10, are at present generally made out of sheet steel or the like for the sake of economy. Accordingly all terminals of the rheostat should be insulated therefrom. The bushing 14, as shown in Figure 10, extends 75 through a hole formed in the panel 55, the bush-

ing 14 being screw threaded as shown. To secure the device in place a nut 56 is screwed onto the bushing 14 on the outside of the panel. To space the terminals 33, 38 and 46 from the metal of the panel I provide, as shown in Figure 6, 5 an annular projection 57 molded integral with the plate 10, this projection being broken away opposite the terminal 38 in case it is desired to ground this terminal by connecting it to the bushing 14. I likewise provide two conical projections 58 which seat in holes in the panel 55 to prevent relative angular movement of the plate 10. When the nut 56 is tightened the plate 10 and all parts of the rheostat are firmly secured in position. The shaft 18 is prevented 15 from movement inwardly of the rheostat by a groove 59 therein which fits a split spring washer 60. It will be seen that shaft 18 and all parts carried by it can be readily inserted in the bushing 14 for assembly of the device prior to 20 insertion of this washer 60. The front of the shaft 18 has affixed to it in any usual or suitable way a knob or handle 61 by means of which the rheostat is controlled. It will be seen that notwithstanding the grounding of certain metal 25 parts of the device, the movable commutator and contact member 22 is insulated from all ground connections unless a deliberate ground connection is made to the bushing by a wire or other means from the terminal 38. 30

Considering now the construction of the resistance 31, and referring particularly to Figures 4, 13, and 14, the base or insulating part 62 is, as already stated, preferably of phenol or similar artificial resin or the like. Upon one surface of 35 this support 62 I apply, as with a brush or otherwise, a basic layer of carbonaceous substance 63. For the substance 63 I prefer a carbon or graphite suspension in phenol varnish. I may use graphite and phenol varnish together, or I 40 may use graphite and lamp black and phenol varnish, and in some cases I use a water solution of one of these carbonaceous substances, with varnish.

After the coating 63 of carbonaceous substance 45 together with some binder is applied to the strip of resin 62, I bake the coated strip at a relatively high temperature for a time long enough to stabilize the resistivity of the coating 63 so that it shall not be subject to any substantial subsequent variation through aging. The baking process also hardens the coating 63, thus protecting against abrasion from the movable contact, renders it impervious to moisture, and the phenol varnish therein to a certain extent unites 55 with the phenol of the base 62 so that practically an integral piece results in which the top layer thereof contains the desired amount of conductive carbonaceous substance.

Considering now the contact arms 23 which, 60 as heretofore stated, are preferably made of Monel metal, as shown in Figures 8 and 9, the arms have semi-circular portions 65 in the center of which is a depression on one side forming a projection 66 on the other which is in the 65 nature of a spherical surface or a surface of the second order to cause the tangency between the arms 23 and the resistance 31 to be somewhat close to a point of contact. In this manner microscopic irregularities or other variations in 70 thickness of the resistance material 63 do not cause sudden shifting of the point at which the major portion of the current between contact and resistance material flows, as in the case of many former constructions utilizing a flat con- 75

tact shoe or one having contact with the resistance element over a wide area. At the same time by the provision of three arms the resistance at the contact and through the contact itself is kept at a low value as compared with the total resistance which is a desideratum in this class of devices. It should be noted, moreover, that the three arms 23 are resiliently urged into engagement with the resistance 31 and consequently contact will be made at each of the three projections 66 irrespective of any variation in the level of the resistance element as between its inside and its outside portions. The three contact points established by the projections are desirably in a radial line so that the three paths of the current will be about equal, thus making the device non-microphonic.

As a result of the use of three contact places each of which is a spherical surface, or other surface of the second order, each contacting point is the lowest point of its finger (eliminating the necessity of accurate alignment), and variations in the resistance element surface do not cause a shift in the locus of contact nor change the contact resistance. Owing to the resiliency of the contact fingers the plurality of contacts is maintained at all times.

I have found that a very satisfactory variable contact is achieved between a rounded surface of 30 Monel metal and a baked graphitic substance including resinous binder. The graphite acts to a certain extent as a lubricant but does not show a detrimental amount of wear over a long period of time and a great many thousand oscillations 35 of the arms 23. Furthermore, it will be observed that the path traced by the projections 66, being relatively narrow as compared with the total width of the resistance element 31, could not cause resistance thereof to be greatly increased 40 even if some of the graphite were eventually worn away, and this is a particular advantage resulting from the use of ball-like projections 66 on resilient contact arms.

Considering now Figure 4, this shows in a developed view an edge elevation of the rheostat disc 10, as though the rheostat were rotated for the draftsman so that the left and right hand ends of the figure represent the same straight line. The split is made at the center terminal 38 50 which is shown half on the left hand side of Figure 4 and half on the right hand side thereof. One of the rivets 32 has in contact therewith a piece of sheet metal 67 like the piece of sheet metal 48 already referred to. This piece 67 is a 55 long arcuate strip having bent-up ears 68 and having a hole for the passage of the rivet 32, and the metal around the hole is pressed into the hole through the disc 10 so that direct contact shall be made between the rivet 32 and the piece 60 of metal 67. The ears 68 are bent over and contact with the sides of the resistance element 31 and with the top thereof for a purpose which will presently be pointed out. The sheet metal piece 48 has corresponding ears 49 which are 65 likewise bent up and over onto the resistance element 31. It is noted that the contact fingers 23 clear all ears 68 and 49.

Referring now more particularly to Figure 13 it will be noted that it is a diagrammatic view, 70 but the general relationship of the parts is similar to Figure 4. Under the head of each rivet 32 I apply a coating 70 of carbonaceous material of relatively good conductivity, and I apply such a coating also under the ears 68 and 49. Distinguishing these coatings by the numerals 70a,

70b and 70c, I note that I apply under the ears 68 to the otherwise completed resistance strip 31 a preliminary coating 71 of relatively highly conductive material. This coating, as shown by the diagrammatic cross-section of Figure 14, extends down the sides of the resistance element 31 as well as across the top thereof. It may be very conductive carbonaceous substance, such as a coating of the nature hereinbefore described for the surface 63 but with a very high proportion of graphite or the like, or it may be a metallic spray or paint. The bent-up portions 68 contact this coating 71 along the sides thus establishing direct low resistance contact between the film of resistance material 63 at the cross-section 14—14 15 and the corresponding terminal 32.

As heretofore indicated the coating 70a is placed over the coating 71. This may be a baked coating of low resistance material of the nature already referred to, but having a resistance somewhat higher than the coating 71. Under the ears 48 and under the coating 70b is another coating 71 of the nature already described, the result in this case being to establish direct electrical contact between the rivet 47 and the carbonaceous 25 substance 63 at the ears 49.

The purpose of applying the coating 71 to the resistance device 31 is to establish a low resistance contact between the ears 68 and 49 of the sheet metal strips 67 and 48, and the resistance 30 element at these particular points. This is established both along the sides and along the marginal edges of the strip 62.

Each of the low resistance coatings 70 serves a further purpose in making a good contact between the rivets 32 and the resistance 63 as the contact resistance between high resistance material and a metal is higher than between a metal and a low resistance, and it is desirable that contact resistance be reduced to a low value. It will be readily appreciated that provision of several distinct means for insuring excellence of contact between the several terminals and the resistance device 31 increases the efficiency of the product considered in bulk. In other words the chances 45 of an individual rheostat and/or potentiometer failing to live up to specifications are much reduced. It will be seen that I may vary the construction of the resistance element and its connection to terminals as desired in order to create 50 a diversity of product for varying uses, and one or more of the means for effecting good contact may, in particular instances, be dispensed with.

Considering now Figures 10, 11, and 12, I mount a snap switch device 75 on the sheet metal casing 51. This snap switch may have terminals 76, and the casing thereof, indicated by the numeral 75 may be of phenol or the like. I shall not herein describe the details of this snap switch as it may be of any usual or desired form, but 60 considering the internal view of Figure 12, it has a pair of ears 77 between which is adapted to enter the rod 30. Figure 12 shows the casing with the rod just leaving the space between the ears 77; upon reverse rotation of the rheostat 65 the rod enters between the ears again and snaps the member 78 supporting ears 77 to the dotted line position of Figure 12. A spring 79 is provided to snap the member 78 to its extreme positions after the rod 30 has started the motion. 70 Inside the casing 75 are knife switch elements connected to the terminals 76 and closed and opened by a movable terminal connected to the member 78; but these parts may be of any usual or desired form and need not be illustrated. The 75

casing 75 may be rigidly secured to the casing 51 by rivets 80 (Figures 10 and 12) and the movable parts of the switch project through a hole 81 in the casing 51. Thus preliminary motion 5 of the knob 61 operates the snap switch 75, which serves the purpose of supplying current to some device, for example a radio set. A certain angular motion of the contact arm is required for this operation and the contact fingers 23, when 10 the switch is closed, are therefore in a position along the resistance element 31 spaced a certain distance XX (see now Figure 16) from the terminal 32. If it were not for the provision of one or more of the several short circuiting devices 15 herein described, the resistance introduced in circuit at this moment would be the resistance of the coating 63 along the arc XX. It is frequently desirable that the resistance at this moment between the variable contact and the nearest terminal (32) be extremely low, for example 20 of the order of 1 to 10 ohms. While the highly conductive coating 70a results in a low resistance, nevertheless it is not always possible thereby to secure a sufficiently low resistance economically. 25 Therefore, desirably I incorporate the strip 67 in my apparatus, locating the ears 68 at the locus of the contacting points of the arms 23 at the moment that the switch makes the radio set operative. It will be seen that the current path 30 at that moment is from the fingers 23 to the ears 68 radially, or if a metal coating 71 is used, merely depthwise through the superimposed coating 70, the remainder of the current path being, in either event, substantially a short circuit. 35 In this manner an exceedingly low resistance is secured which could not otherwise be obtained.

It will thus be seen that there has been provided by this invention a method and apparatus in which the various objects hereinabove set forth, together with many thoroughly practical advantages, are successfully achieved. It will be further seen that I have provided a switch and rheostat or potentiometer particularly applicable 45 for use as a volume control in a radio apparatus, and that the construction shown can be connected in circuit in a great variety of ways to suit the requirements of particular radio manufacturers, and thus the product has a high degree of universality and may be a standard product for use in a great number of different radio circuits or electrical apparatus.

As various possible embodiments may be made of the above invention, and as many changes 55 might be made in the embodiment above set forth, it is to be understood that all matter hereinbefore set forth or shown in the accompanying drawings is to be interpreted as illustrative and not in a limiting sense.

60 I claim:

1. In apparatus of the class described, an insulating base, a bushing in said base, a shaft mounted in said bushing, a disc of insulating material mounted on said shaft, a metallic disc 65 mounted on said insulating disc, a plurality of fingers integral with said metal disc, a horseshoe shaped piece of resistance material mounted on said base contacted by said plurality of fingers, a terminal and lead connected near one end of 70 the horseshoe to said resistance material, and a lead connected at an intermediate portion of the horseshoe and comprising a metallic plate under said resistance material having ears extending therefrom and in contact with marginal edge 75 portions of said resistance material, whereby a

smooth unbroken path is provided for the contacting ends of the plurality of fingers despite the connection of the lead at an intermediate portion of the horseshoe.

2. In apparatus of the class described, a base, 5 a rotatable shaft mounted in said base, a plurality of metal fingers carried by said shaft, a horseshoe shaped piece of resinous insulating material mounted on said base, a baked coating of carbonaceous substance on said horseshoe 10 shaped piece, and spherical shaped projections formed on said metal fingers to form point contacts with said baked coating, the points of contact of said projections and said coating being in a radial line with respect to the axis of said 15 shaft.

3. In apparatus of the class described in combination, a resistance strip, means forming a contacting part engaging said strip and adapted to move therewith, a terminal connection substantially at one end portion of said strip including a pair of elements engaging the sides of said strip and spaced from said last mentioned end thereof, a switch in the circuit of said terminal, and means associated with said switch and said part adapted 20 to close said switch when the contacting portion of said part is substantially adjacent said elements.

4. In apparatus of the class described in combination, a resistance strip, a contacting part, 30 means adapted to move said part along said strip and in engagement with said strip, a terminal structure connected to said strip and having elements contacting said strip at points spaced from the ends thereof, the portion of said strip adjacent said elements being of much greater electrical conductivity than the remaining portion of said strip, a switch in the circuit of said terminal structure, and means associated with said part and adapted to actuate said switch when the 40 contacting portion of said part engages said last mentioned portion of said strip.

5. In apparatus of the class described, in combination, an insulating base, a substantially circular shaped flat strip having electrical conductivity of high resistance value mounted on said base, a shaft rotatably mounted in said base so that its axis of rotation passes through the center point of said strip, an armature arm connected to said shaft and shaped to engage said strip so 45 that rotation of said shaft moves the contacting portion of said arm along said strip, means forming a terminal connection at one end portion of said strip including an ear engaging a side of said strip at a point spaced from the end to which said terminal is connected, a snap switch connected to said base, and means associated with said arm and said switch adapted to move said switch to its on position as the contacting portion of said arm reaches a point adjacent said ear 55 in its path of travel from said last-mentioned end of said strip.

6. In apparatus of the class described, an insulating strip, a coating of high resistance material baked upon said strip, a narrow band of low resistance material painted across said strip, a piece of sheet metal on the side of said strip opposite said coating, and ears extending up around the edges of said strip and in contact with said 60 narrow band.

7. In apparatus as claimed in claim 6, the combination with the elements therein specified of a coating also extending along the edges of said strip to establish contact between said piece of 70 75

sheet metal and said high resistance coating through said coating on the edges.

8. In apparatus of the class described, in combination, a strip having a flat surface of substantial length, said strip being an electrical conductor of high resistance, an armature arm adapted to engage said strip, means adapted to move said arm along said strip, a terminal connection at one end portion of said strip including a pair of parts engaging the sides of said strip and spaced from said last-mentioned end thereof, a switch adapted to be placed in the circuit of said terminal, and means associated with said switch and said arm adapted to close said switch when the contacting portion of said arm is in substantial alignment with said parts.

9. In apparatus of the class described, a horse-shoe shaped strip, said strip being a conductor having a high resistance, an arm, means rotatably mounting said arm substantially at the axis of said strip, and means connected to said arm and contacting said strip at minute spaced points along a radial line of said axis.

10. In apparatus of the class described, a horse-shoe shaped strip, said strip being a conductor having a high resistance, an arm, means rotatably mounting said arm substantially at the axis of said strip, and means forming a plurality of fingers connected to said arm and engaging said strip at minute spaced points, said points being in a radial line of said axis.

11. In apparatus of the class described, a horse-shoe shaped strip, said strip being a conductor having a high resistance, an arm, means rotatably mounting said arm substantially at the axis of said strip, and means including a plurality of resilient fingers having semi-spherical projections engaging said strip at minute spaced points in a radial line of said axis.

12. In apparatus of the class described, a circular strip having a flat surface of substantial length, said strip being an electrical conductor of high resistance, a plurality of contact parts engaging said strip at minute spaced points in a line substantially at right angles to the center line of said strip, and means connected to said contact parts adapted to hold them in said relationship with said strip and move them from end to end.

13. In apparatus of the class described, a circular strip having a flat surface of substantial length, said strip being an electrical conductor of high resistance, a plurality of contact parts engaging said strip at minute spaced points in a line substantially at right angles to the center line of said strip, an arm connected to said contact parts, and means holding said arm in fixed relationship to said strip, said arm being capable of movement along said strip whereby said contact points are maintained in said relationship during movement between the ends of said strip.

14. In apparatus of the class described, a strip having a flat surface of substantial length, said strip being an electrical conductor of high resistance, a plurality of contact parts engaging said strip at minute spaced points in a line substantially at right angles to the center line of said strip, means connected to said contact parts adapted to hold them in said relationship with said strip and move them from end to end thereof, and means forming a terminal connection intermediate the ends of said strip including a part engaging the side of said strip and spaced from the ends thereof to form an electrical connection therewith, said means leaving

an unobstructed surface in the path of travel of said contact points.

15. In apparatus of the class described, a strip having a flat surface of substantial length, said strip being an electrical conductor of high resistance, a plurality of contact parts engaging said strip at minute spaced points in a line substantially at right angles to the center line of said strip, means connected to said contact parts adapted to hold them in said relationship with said strip and move them from end to end, means forming a terminal connection intermediate the ends of the said strip including a part engaging the side of said strip to form an electrical connection therewith, said means leaving an unobstructed surface in the path of travel of said contact points, and a substance of greater conductivity than said strip interposed between said part and the side of said strip.

16. In apparatus of the class described, a strip having an elongated flat surface, said strip being an electrical conductor of high resistance, a commutator arm adapted to engage said surface and travel therealong from end to end, a terminal member disposed intermediate the ends of said strip and engaging a side thereof to leave said surface unobstructed, and a substance interposed between said terminal and the side of said strip of greater conductivity than said strip.

17. In apparatus of the class described, a strip having an elongated flat surface, said strip being an electrical conductor of high resistance, a commutator arm adapted to engage said surface and travel therealong from end to end, a terminal member disposed intermediate the ends of said strip and engaging a side thereof to leave said surface unobstructed, and means forming separate electrical connections with the opposite ends of said strip.

18. In apparatus of the class described, a strip having an elongated flat surface, said strip being an electrical conductor of high resistance, a commutator arm adapted to engage said surface and travel therealong from end to end, a terminal member disposed intermediate the ends of said strip and engaging a side thereof to leave said surface unobstructed, and means forming separate electrical connections with the opposite ends of said strip, a section of the strip adjacent one end thereof being of greater conductivity than the remaining portion of said strip.

19. In apparatus of the class described, a strip having a top surface of substantial length, said strip being an electrical conductor of high resistance, means forming a terminal connection with one end of said strip and comprising a flat piece of metal extending beneath said strip throughout a portion of the length thereof, an ear in engagement with the side of said strip to leave said top surface unobstructed, and means forming a terminal connection intermediate the ends thereof including a part engaging the side of said strip to leave said top surface unobstructed.

20. In apparatus of the class described, in combination, an insulating base, a flat substantially circular strip secured to said base, a conducting coating on the exposed flat surface of said strip, a shaft rotatably mounted in said base, an arm secured to said shaft, a plurality of fingers secured to said arm adjacent said strip, said fingers being shaped to engage said strip at spaced points, a terminal structure connected to one end of said strip and having a pair of ears adjacent the edges of said strip intermediate the

ends thereof, a switch in the circuit of said terminal, and means forming a mechanical connection between said switch and said arm adapted to close said switch when the contacting points of said fingers are substantially adjacent said ears in their movement from the end of said strip to which said terminal structure is connected.

21. In apparatus of the class described, an insulating strip, a coating of high resistance material upon said strip, a band of low resistance material deposited across said strip, a piece of sheet metal on the side of said strip opposite said coating, and ears extending up around the edges of said strip and in contact with said band.

22. In a variable resistance device, a resistance element, a contactor, means for moving said contactor over the surface of said resistance element in a predetermined path, a terminal extending around the greater portion of the resistance element in a plane transverse to the line of movement of said contactor and a gap in said terminal through which the contactor is adapted to be moved, said terminal having intimate contact with said resistance element adjacent the path of the contactor.

23. A variable resistance device comprising a resistance element, a contactor movable along the contact surface of said resistance element, and a terminal having a portion extending transversely partially around said resistance element and having its ends bent over into engagement with the contact surface of said resistance element and spaced apart to permit the passage of said contactor between said ends.

24. In apparatus of the class described, a strip having an elongated flat surface, said strip being an electrical conductor of high resistance, a commutator arm adapted to engage said surface and travel therealong from end to end, a terminal structure disposed intermediate the ends of said strip and engaging a side thereof to leave said surface unobstructed, said structure including a metallic part and a highly conductive substance

interposed between said part and said strip, and means forming separate electrical connections with the opposite ends of said strip.

25. In apparatus of the class described, a strip having an elongated flat surface, said strip being an electrical conductor of high resistance, a commutator arm adapted to engage said surface and travel therealong from end to end, a terminal structure disposed intermediate the ends of said strip and engaging a side thereof to leave said surface unobstructed, said structure including a metallic part and a highly conductive material contacting said part and extending transversely across said strip, and means forming separate electrical connections with the opposite ends of said strip.

26. In apparatus of the class described, a strip having an elongated flat surface, said strip being an electrical conductor of high resistance, a commutator arm adapted to engage said surface and travel therealong from end to end, a terminal structure disposed intermediate the ends of said strip and engaging a side thereof to leave said surface unobstructed, said structure including a metallic part and a highly conductive coating comprising a carbonaceous material and a binder contacting said part and said strip, and means forming separate electrical connections with the opposite ends of said strip.

27. In apparatus of the class described, a strip having an elongated flat surface, said strip having a coating of high resistance material on one surface thereof, a commutator arm adapted to engage said coating and travel therealong from end to end, a terminal structure disposed intermediate the ends of said strip and engaging a side thereof to leave said surface unobstructed, said structure including a metallic part and a highly conductive substance interposed between said part and said coating, and means forming separate electrical connections with the opposite ends of said strip.

JESSE MARSTEN.

CERTIFICATE OF CORRECTION.

Patent No. 2,101,441.

December 7, 1937.

JESSE MARSTEN.

It is hereby certified that error appears in the printed specification of the above numbered patent requiring correction as follows: Page 2, second column, line 3, for "furtherfore" read furthermore; page 6, second column, line 11, claim 15, after "end" second occurrence, and before the comma, insert thereof; line 14, same claim, after "strip" insert and spaced from the ends thereof; line 50, claim 18, for "end" read of said connections; and that the said Letters Patent should be read with these corrections therein that the same may conform to the record of the case in the Patent Office.

Signed and sealed this 8th day of February, A. D. 1938.

(Seal)

Henry Van Arsdale,
Acting Commissioner of Patents.
